LARS G. NILSON AND JULIUS ABEGG, OF HOBOKEN, NEW JERSEY, ASSIGNEES OF ONE-HALF TO THOMAS J. WILSON AND ONE-HALF TO SAID ABEGG, BOTH OF HOBOKEN, NEW JERSEY.

STYLOGRAPHIC FOUNTAIN-PEN.

1,244,070.

Specification of Letters Patent.

Patented Oct. 23, 1917.

Application filed June 21, 1916. Serial No. 104,835.

To all whom it may concern:

Be it known that we, LARS G. NILSON and JULIUS ABEGG, citizens of the United States, residing at Hoboken, N. J., have invented 5 certain new and useful Improvements in Stylographic Fountain-Pens, of which the following is a clear, full, and exact description.

This invention relates to an improvement 10 in stylographic pens and has for its object to simplify the construction of the same and to obtain improved results therefrom.

Stylographic pens as at present constructed usually have a writing member consisting 15 of a fine wire forming a single needle-like writing point. Such a writing point has very little flexibility, and, moreover, when the ink dries thereon between the different times when it is used, it is apt to become 20 clogged and prevent the easy flow of ink to the paper. To overcome these objections we propose a writing member formed of a plurality of needle-like wires closely bundled together to provide ink flowing channels 25 along their adjacent sides and between them, and so attached to their support as to be capable of independent flexing movement and thus insure an easy flow of ink therefrom at all times.

30 We also propose forming the different parts of the pen in such a way as to make them easily detachable for cleaning and for filling the pen, and for the purpose of replacing worn out or broken parts.

35 A still further object is to provide a construction wherein the flow of ink to the writing point may be adjusted for fine or heavy lines and to even be shut off entirely when desired.

40 Other objects and advantages of our new construction will become apparent from the following detailed description and accompanying drawings.

In the drawings which show the preferred 45 embodiment of our invention, Figure 1 is a view of the entire pen;

Fig. 2 is an enlarged detail of the lower end thereof partly in section;

Fig. 3 is a view of the main point section 50 and supplemental point section, the former being in longitudinal section;

Fig. 4 is a detail longitudinal section through the main point section and supplemental point section, showing the mounting 55 of the feed-bar and the writing member;

Fig. 5 is a cross-section along line 5—5 of Fig. 3;

Fig. 6 is a cross-section through the writing member along line 6—6 of Fig. 7;

Fig. 7 is an enlarged detail of the lower 60 portion of the writing member; and

Fig. 8 is a top end view of the feed-bar.

Fig. 9 is an enlarged detail of the writing member with the front wire removed.

Referring more particularly to the drawings, the pen comprises the usual ink barrel 65 5 having an ink reservoir 14 within the same, a cap 6, main point section 2, supplemental point section 1, and a writing member 4.

The main point section may be mounted 70 upon the barrel of the pen by screw-threaded engagement therewith as is customary, and within the main point section and carried thereby is preferably mounted the feed-bar 75 3, also screw-threaded therein as shown. The upper end of the feed-bar communicates with the interior of the ink reservoir 14 and has ink feeding grooves 9 along its sides leading toward the lower end thereof. The 80 lower portion of the feed-bar is preferably tapered as shown in Fig. 4, and has securely fixed in its lower end at 15 the writing member 4.

The writing member 4 is formed to provide 85 a plurality of separate and co-acting needle-like points and consists preferably of a number of independent straight wires laid contiguously in parallel relation, as shown in Figs. 6 and 7, so as to provide ink flowing 90 channels 4' along their sides and between them. The number of wires thus bundled together may be varied, although we prefer three or more wires laid together, and in the present embodiment have shown four of such 95 wires. The wires terminate evenly, and their lower ends are also preferably tapered, as shown at 9, to a common central axis of the group and thus provide a line marking 100 element which is suitable for writing and 100 which will give service upon any side of the writing member which happens to be put against the paper, as in the case of the ordinary stylographic needle point. Moreover, 105 since the separate wires making up the writing member are independently mounted, they have a flexing movement one upon the other in use and thus tend to break up clots of dried ink thereon and insure an easy flow 110 of ink to the point of application on the

paper. The writing member may of course be formed in other ways than by the bundling of wires together as we have shown, the essential feature being to provide a plurality of such coacting needle-like points.

The writing member 4, as it extends from within the main point section 2, is inclosed within a supplemental point section 1 preferably screw-threaded at its upper end with-
10 in the lower end of the main point section 2. The lower end of the supplemental point section 1 is provided with the usual bushing of metal 10. The inner peripheral corner 12 at the upper end of the supple-
15 mental point section 1 is adapted to engage the lower tapered portion of the feed-bar 3 at a line below the ink feeding grooves 9 and the supplemental point section 1 may be adjusted on its screw-threaded engage-
20 ment with the main point section 2 to bring about this contact or to vary the space be-
tween the edge 12 of the supplemental point section and the feed-bar 3 to adjust the flow of ink down the feed-bar and on to
25 the writing member 4. Of course when the supplemental point section 1 is screwed tightly to bear against the feed-bar 3, the flow of ink is entirely shut off. The en-
larged threaded upper end of the supple-
30 mental point section 1 is preferably pro-
vided with a slot 7 with perforations 8 extending therefrom through the wall of said supplemental point section 1 and thus provide an air vent to the space surround-
35 ing the feed-bar. This provides for atmos-
pheric pressure within the ink reservoir to permit the easy flow of ink therefrom, as is well understood.

We do not wish our invention to be lim-
40 ited to the specific constructions above de-
scribed and shown in the drawings, as it is obvious that various changes in detail and arrangement of the parts may be made without departing from the essential char-
45 acteristics of the invention.

What we claim as new is:—

1. A stylographic writing pen comprising a plurality of contiguous straight wires coacting at one end to form a stylographic
50 point suitable for writing.

2. A stylographic writing member comprising a plurality of contiguous straight

wires with their ends terminating evenly and coacting to form a stylographic writing point.

55

3. A stylographic writing member comprising a plurality of contiguous straight wires laid together to provide ink flowing channels between their sides and with their ends terminating evenly and coacting at 60 said ends to form a stylographic writing point.

4. A stylographic writing member comprising a plurality of contiguous straight wires independently flexible with their ends terminating evenly and coacting at said ends to form a stylographic writing point.

65

5. A stylographic writing member comprising a plurality of contiguous straight wires with evenly terminating ends tapered 70 toward a common central axis of the group, said ends coacting to form a stylographic writing point.

70

6. In a stylographic pen, in combination, a pen holder, a writing member comprising 75 a plurality of contiguous straight wires supported in said holder and coacting at one end to form a stylographic writing point, and a member embracing said wires for supporting the same adjacent the writ-
ing point.

75

7. A stylographic writing member comprising, in combination, a feed bar, a plurality of wires fixed at one end in said feed bar and laid contiguously with their other 85 ends terminating evenly to form coacting writing points, and a point section inclosing said contiguous wires and forming a bearing support therefor slightly above the writing points.

90

8. A stylographic writing member, comprising a plurality of independently mounted wires normally in contact throughout their length and coacting at their free ends to form a stylographic writing point and a member embracing said wires for supporting the same adjacent the writing point.

95

Signed at New York, N. Y., this 6" day of June, 1916.
